ARCH-SUPPORTING FOOTWEAR.

Application filed August 17, 1927. Serial No. 213,452.

This invention relates to footwear for human beings and it has more particular reference to boots and shoes designed to scientifically support the arch of the foot.

Footwear as a means of protection for the feet is an art in itself and has been materially advanced by modern machinery, the tanning of leathers used in their manufacture, and the use of diverse compositions intended to reduce foot strains in the act of walking, standing for long periods, and so forth. However, despite all such improvements, it has been impossible to produce footwear that strictly conforms with the normal action of the various joints of the human foot; or, in other words, the functions of the human foot and the movements of the footwear, up to the present time, have not been harmoniously attuned or balanced.

Generally, the soles of boots and shoes embody an inner element, an outer element, and a heel, with a filler interposed between said sole elements before sewing or nailing together. These fillers are usually cut from sheets composed of ground cork with a suitable cementitious binder, and they are inserted to prevent "squeaking" in the act of walking. After such footwear have been in use for a length of time, the normal heat of the foot, as well as the "push-off" in walking, cause a shifting of such fillers backwards—relative to the soles—and thus create a marked concavity on the inner side of the inner sole. This concavity is most pronounced in the region of the big toe, and the second and third toe joints, against which the anterior metatarsal regions of the foot fall, which results in an overstretching of the plantar muscles and a contraction of the dorsal muscles. In turn there is effected a weakening of the tibialis anticus and the tibialis posticus muscles, which assist in holding up the longitudinal and transverse arches of the foot, and as said arches are sustained by the foot muscles, tendons, and ligaments, when functioning properly, it is highly important that no impedance or resistance to their natural functioning be encountered, as any interference therewith invariably produces "flat" or weak feet.

The primary object of this invention is to effectively overcome the foregoing disadvantages, noted as existent in ordinary footwear, by providing a scientifically correct supporting position for the transverse arch

of the foot under all normal conditions, no matter whether the arch be "fallen" or otherwise, while affording free natural movement for the foot bones and muscles.

Another object is to furnish footwear which preserve their original correct shape, while the "filler" above referred to is effectively prevented from creeping or otherwise setting up any irregularity in the region supporting the ball of the foot and the transverse arch.

Other objects and advantages incident to my invention will be manifest from the following detailed explanation which, when considered in connection with the accompanying drawings, illustrates a practical embodiment thereof; while the appended claims define those features alleged as novel in the art and on which patent protection is desired.

Tersely stated, my invention essentially consists of a relatively pliable unitary device, fitted into the soles of footwear, which correctly supports the transverse arch of the foot from the ground; that continues to do so as the footwear wears down in use; and, which also acts in the capacity of a "dam" to prevent formation of irregularities at the ball of the soles and in the region of the shank or arch.

In the drawings:—

Fig. I is an underside plan of a man's or boy's shoe, with a portion of the outer sole broken away to better disclose the insert member constituting the fundamental of my present invention.

Fig. II is a part side—and part sectional—view of the same, with the major portion of the upper removed for convenience in illustration.

Fig. III is a sectional view, taken as indicated by the arrows III—III, in Fig. I.

Fig. IV is a perspective view of the insert above referred to; and,

Fig. V is an enlarged end view looking in the direction of the arrow —V— of the preceding illustration.

Referring more in detail to the drawings a standard style of shoe, for men, women or children, is comprehensively designated by the numeral 6; the same embodying an upper 7, outer sole 8, filler 9, inner sole 10 and heel 11, all conventionally attached together in accordance with known methods.

My novel insert member—or what I pref-

erably term a metatarsal bar—is designated generally by the reference character 12, and as best appreciated from Figs. IV and V, it will be observed the same is of irregular—
5 though scientific—contour. More specifically this metatarsal bar 12 is shaped, or otherwise formed from rubber, leather, or other suitable flexible sheet material, to provide a straight side 13, that is chamfered
10 down to a substantial knife edge as indicated at 14, a similarly beveled narrow end 15, an undulate side 16, and a portion 17 that is of a profile to conform with the inner border outline of the sole 8 intermediate
15 the ball or tread portion 18, along and upwardly in alignment with the shank 19, as clearly seen on reference to Fig. I, more particularly. In other words, the insert bar 12 is fashioned—as clearly shown—to conform with the shape of the anterior metatarsal arch of the foot. Particular attention is directed to the fact that the profile portion 17, above referred to, is hollowed out at 20 and upwardly flexed or raised;
20 so that when applied in a shoe with the edge 17 snugly fitting alignedly between the border edges of the inner sole 10 and outer sole 8, the bar 12 is designed to transfer or deflect the weight from the inner side to the
25 outer side of the foot. Accordingly, this anterior metatarsal or insert bar 12 is located scientifically in the footwear under the ball of the foot as defined by the sesamoid bones of the big toe, and the second,
30 third, and fourth metatarsal-phalangeal articulations. This relation results from its own unconstrained configurations as molded or otherwise shaped.

When pressure is applied, in the act of
35 walking, the insert bar 12 supports the weight firmly; while such flexure as is necessary to adapt or fit said bar in a shoe effects a slight upward curvature thereof, so that it fits closely against the shank of
45 the filler 9, and thereby obviates any tendency of the latter to "creep" in either direction; or, to work away from its initial position.

In the illustrated application of my invention, it will be noted, the insert bar 12 is secured by stitching 21 between the customary welt 8'—Figs. II and III—attached around the inner sole 10 and the outer sole 8; but, it may be attached to either of said soles by means of tacks, brads or screws. Again, as will be apparent, it is not necessary to remove the entire outer sole 8, to insert the bar 12, and secure the same in proper position.

60 Shifting of the filler 9, as before mentioned, in shoes of ordinary make, is initiated by the normal heat of the foot and the "push-off" in walking after a shoe has been in service for some time, and by backward pressure—incident to the bend or flex-

ion of the foot at the point where the sole 8 of the shoe and shank 19 meet—said filler is gradually forced into the space intervening the inner and outer sole portions embodied in said shank. My novel insert 12 70 is particularly effective to counteract any such "creeping" of the filler 9 by serving as a "dam" which prevents said filler from working backward, by maintaining the same in proper location relative to the inner and outer soles 10, 8, at all times. The insert bar 12 thus, not only also prevents weakening of the shoe transverse arch but similarly counteracts any tendency of the upper 7 to buckle or crease in the region of the shanks 80 19. Again, the insert bar 12 being initially raised or arched upwardly at 20 on the inner border of the shoe 6 at the point where most of the body weight is concentrated when walking, and by merging the same 85 toward the outer border of the shoe with respect to the most flexible part of the foot, as well as by keeping the filler 9 in its proper place; effectively prevents formation of any concavity in the shoe sole as said sole wears down. These features are of vital importance and fundamentally distinguish my invention over all known arch supports for the scaphoid, middle and external cuneiform bones of the human foot. 90

Furthermore, the bar 12, by virtue of its scientifically designed formation, possesses no distorting tendency of its own, in that it does not lift the "keystone" of the transverse arch while leaving its inner side unsupported. When pressure is applied to the tread or bearing surface of the foot in walking, on my universally yielding and resiliently flexible insert 12, the wearer's weight is evenly, firmly and yieldingly supported from the ground; while the fatigue resulting from immobility of the muscles incident to the prior use of rigid and unyielding metal and similar braces is, obviously, avoided. The device 12 as a unit does not affect the normal yield of the shoe at the ball 18, but, on the contrary, permits it to accommodate itself freely to the foot and the ground. On the other hand, the device 12 not only supports the sesamoid bones and the metatarsal-phalangeal articulations under all conditions, thereby preventing the foot bones generally from assuming any abnormality tending to cause anterior metatarsalgia, but it relieves and functions to rectify such a condition. 110

From the foregoing it is thought the invention will be fully appreciated, and while I have described the same with some degree of particularity; the right is hereby reserved to make such variations in shape—to adapt said invention to different types of footwear—as are fairly encompassed by reasonable interpretation accorded the subjoined claims. 125 130

Having thus described my invention, what I claim is:—

1. As an article of manufacture a resilient member, for attachment transversely intermediate the inner and outer soles of footwear and rearwardly from the metatarsal arch, said member extending across the soles from edge to edge and embodying a forwardly directed chamfered straight edge, a rearward correspondingly-chamfered undulate portion, a reversely chamfered slightly-raised edge conforming with the inner border edges of the footwear sole, and a comparatively narrow beveled edge aligned with the outer border edge of said sole.

2. As an article of manufacture a resilient member for attachment transversely intermediate the inner and outer soles of footwear and rearwardly from the metatarsal arch, said member extending across the soles from edge to edge and of a configuration to occupy a plane commencing from a point at the inner border of the sole—known as the ball—and extending to the outer side of said ball at an elevation higher on the inner side and rearwards to afford support under the metatarsal bone of the big toe at a gradual slope towards the internal cuneiform bone, and also sloping downward to the region of the fourth metatarsal bone of the wearer's foot to provide similar support therefor.

3. Footwear for human use embodying an

insert member attached transversely between the inner and outer soles as well as from edge to edge thereof in the region rearward of the ball of the foot; said member having a forward tapering straight edge, a rear undulate chamfered edge, a slightly raised hollowed-out edge registering with the inner border edge of the footwear sole, and a comparatively narrow beveled edge aligning with the outer border edges of said sole; said member, also, effectively preventing backward creeping of the sole filler.

4. Footwear for human use embodying an insert member attached transversely between the inner and outer soles as well as from edge to edge thereof in the region rearward of the ball of the foot; said member having a forward tapering straight edge, a rear undulate chamfered edge, a slightly raised hollowed-out edge registering with the inner border edge of the footwear sole, and a comparatively narrow beveled edge aligning with the outer border edge of said sole; said member supporting the sesamoid bones of the wearer's foot—as well as the metatarsal-phalangeal articulations—under all conditions, and effectively preventing creepage of the sole filler backwards.

In testimony whereof, I have hereunto signed my name at Penn Yan, New York, this ninth day of August, 1927.

HENRY A. GARTNER.
